ATTORNEY.

UNITED STATES PATENT OFFICE.

GOTTFRIED GRILL, OF BALTIMORE, MARYLAND:

ROSETTE-MACHINE.

SPECIFICATION forming part of Letters Patent No. 245,817, dated August 16, 1881.

Application filed June 17, 1881. (No model.)

To all whom it may concern:

Be it known that I, GOTTFRIED GRILL, of Baltimore city, State of Maryland, have invented certain new and useful Improvements 5 in Rosette-Machines; and I hereby declare the same to be fully, clearly, and exactly described as follows, reference being had to the accompanying drawings, in which—

Figure 1 is a front and Fig. 2 a side elevation of the machine. Fig. 3 is a sectional view on the line *x x* of Fig. 1, and Fig. 4 is a plan of the pawl for actuating the discharging mechanism.

My invention relates to machines for cutting 15 wood rosettes to be used as ornaments or escutcheons for furniture; and it consists in certain details of construction and combinations of parts, as hereinafter set forth and claimed.

In the drawings, A is the main frame, in 20 which are journaled in bearings *a a b b* the shafts B and C. The shaft C carries a pulley, *c'*, for the driving-belt, and on its inner end is mounted the cutter-head E, having blades *e* of any desired contour. The shaft B carries also a pulley, *c*, for its driving-belt, and on the end of the shaft is mounted a cutter, D, having one or more peripheral blades, *d*, exactly similar to the side lips of an ordinary auger.

F is a frame which slides in a direction parallel to the axes of the shafts B and C, which are accurately in alignment. The frame F is normally drawn upward by springs G, that are connected with the frame by wires *f f*, as shown.

H is a table or plate secured to the frame F, 35 and extending outward between the cutters D and E in a direction at right angles to the shafts B and C. It has a front handle, *h*, by means of which the table and frame are raised and lowered, and is provided with an aperture, *h'*, through which the cutters pass.

I is a block secured to the table H, and to it is hinged at *i* the plate J, having an aperture, *j*, for the entrance of the cutter D.

L is a lever (see Fig. 3) pivoted to the table 45 H, having a recess, *r*, adapted, as hereinafter described, to be brought opposite the orifice *h'*. The lever is normally thrust toward the stop *m* by means of a spring, *n*, its lower end traveling against a curved guide, N.

50 A pawl, *p*, is mounted on the frame A, and a pin, *p'*, secured to the rear edge of the table

H engages with the end *p''* of the pawl, bringing its end *p'''* in the line of motion of the lower end of the lever L. A spring, *s*, serves to return the pawl to its normal position.

In operation the shafts B and C are caused to revolve, and the board from which the rosettes are to be cut is laid upon the table H. The plate J is then brought down upon the board, and the projecting end of the plate and the handle *h* being grasped by the operator, the board is securely clamped. The entire frame is then pressed down toward the cutter-head E, pending which motion the lower end of the lever L traverses the curve N, and the upper end moves away from its position opposite the hole *h'*. The cutter-head passes through the hole and cuts the rosette on the face of the board clamped between the table H and plate J. At the same time the pin *p'* encounters the end *p''* of the pawl *p* and tilts its lower end, *p'''*, opposite the path of the lower end of the lever, causing the upper end to tilt backward slightly against the resistance of the spring. As the lower end of the lever passes the end *p'''* of the pawl the spring *n* throws the lever over against the stop *m*, discharging a previously cut rosette into a suitable basket. As soon as the face of the rosette is formed by the cutter E, the frame F is lifted against the cutter D, which enters the rear face of the board and cleanly cuts out the rosette. The latter falls through the hole *h'* into the recess in the upper end of the lever L, which, pending the upstroke of the frame F, has come opposite the hole. The board is then moved forward, the frame is depressed, and the severed rosette is thrown out by the lever, as above described.

The machine is rapid and accurate in its work, furnishing rosettes with smooth, clean-cut edges, which possess the double advantage over those hitherto made of fitting closely in countersunk mortises and of presenting a neat appearance when glued on the face of the article of furniture.

Instead of bringing the work to the cutters, the latter may be made to approach and recede from the work; but the described construction is to be preferred.

What I claim is—

1. In a rosette-machine, a reciprocating table for holding the work, in combination with

a pair of shafts carrying respectively a cutter for forming the face of the rosette and a severing-cutter and mechanism for reciprocating the table between the cutters, as set forth.

5 2. In combination with the shafts and cutters, the sliding frame F, table H, and plate J, as set forth.

3. In combination with the shafts and cutters, the table H, having orifice h' , and the 10 hinged plate J, having orifice j , as set forth.

4. In combination with the shafts and cut-

ters, the sliding frame and clamp, and the lever L and pawl p , as set forth.

5. In combination with the shafts and cutters, the sliding frame and clamp, the lever L, 15 having recess r , the pawl p , and spring n , as and for the purpose set forth.

GOTTFRIED GRILL.
